CEREAL CANISTER

Robert L. Santuci, Sr., Buffalo, N.Y.

Application May 3, 1957, Serial No. 656,921

1 Claim. (Cl. 222—183)

This invention relates to containers or canisters, and more particularly has reference to a device of this nature adapted for holding an opened box of cereal.

The present practice with respect to the dispensing of the various dry cereals is to partially tear away the top portion of the carton or package in which the cereal is merchandized. Alternatively, scored lines may be provided upon the carton to permit the same to be punched inwardly or outwardly, for the purpose of forming a dispensing opening. Within such a carton there is usually provided a waxed bag, which must also be opened. All in all, the general practice required in the dispensing of cereals of this type is somewhat inconvenient, untidy, and annoying.

In view of the above, among other important objects of the invention there are the following:

To provide a canister which will be particularly adapted to hold a conventional box of cereal, in a manner which will provide for neat and sanitary maintenance of the cereal in a fresh condition;

To facilitate the preparation of the conventional cereal box for use in the canister or dispensing container, by reason of a canister construction such that the cereal box is prepared for dispensing merely by cutting off the top of the cereal box and of the inner sack or bag;

To permit the canister to be used as the container in which the cereal may be directly poured from the carton in which it is normally sold;

To define a pouring spout which will markedly facilitate the pouring of the cereal;

To so form the canister that the advertising material displayed upon the carton will still be clearly visible; and

To provide a canister which will achieve all the several desirable objects set forth above while still being capable of manufacture at a low cost.

Other objects will appear from the following description, the claim appended thereto, and from the annexed drawing, in which like reference characters designate like parts throughout the several views, and wherein:

Figure 1 is a perspective view of a canister according to the present invention;

Figure 2 is a sectional view therethrough substantially on line 2—2 of Figure 1, the dotted lines showing the cap in open position; and

Figure 3 is an exploded perspective view of the canister, portions being broken away.

Referring to the drawings in detail, designated generally at 10 is a receptacle including a bottom wall 12, front and back walls 14, and side walls 16. Most usually, a conventional cereal carton such as has been generally designated at 18 is of rectangular configuration, and accordingly, the receptacle 10 is formed complementarily to the conventional cereal carton. It will be understood, however, that the canister could be designed to fit a particular carton of cereal, and therefore, the receptacle can be of any shape desired, for matching the shape of the cereal carton.

2

In the illustrated example, there is a flat bottom wall 12, and vertical front, back and side walls.

The receptacle 10 is formed wholly open at its upper end, so as to snugly receive the carton 18 in which the cereal is sold. The carton is somewhat greater in height than the receptacle, although this is not essential to successful operation of the invention.

To prepare the carton for use in the dispensing container, it is merely necessary that the top of the carton, 10 and any inner bag that may be provided in the carton, be cut off as at 20, to form an opening in said top. The top of the carton could be cut off completely if desired. In any event, the carton, after being formed with an opening 20 as described, is thereafter covered by a cover portion 22 of the device. The cover portion 22 includes a flat top wall 24 formed with a depending, continuous, peripheral flange 26, the flange 26 having in its bottom edge a continuous, downwardly opening, narrow groove 27 the outer wall of which extends downwardly a greater distance than the inner wall in the illustrated embodiment, as clearly shown in Figure 2. Thus, the cover portion is snugly, sealably fitted onto the upwardly opening receptacle, and the side walls of different heights on groove 27 facilitate the entrance of the top edge portion of the receptacle into the groove. This is because the longer, outer side wall first engages the walls of the receptacle, and guides the same into the space between the outer and inner walls of the groove.

At one end of the top wall 24, the same is formed with an upwardly projecting, low rectangular pouring spout 28 extending the full width of the cover portion. A dependently flanged, rectangular cap 30 is adapted to be fitted upon the neck 28, and is provided with a U-shaped support yoke 32, the bight portion of which is adapted to snap into an upwardly opening groove 33 formed in a transverse rib 34 integral or otherwise made rigid with the top wall 24 adjacent spout 28. The groove 33 has a reduced top portion 36 as best shown in Figure 2, said constriction or reduced entranceway of the groove being slightly narrower than the diameter of the bight portion of the support yoke 32, with the side walls of the reduced entranceway being adapted to spring apart to permit the entrance of the support yoke.

The cap 30 is thus swingably mounted for movement between its closed and open positions, shown in full and dotted lines respectively in Figure 2.

In use of the device, when the cereal is to be dispensed, the device is tilted, and the cap 30 is swung to open position, to permit the contents to be poured through the spout. In this way, a neat, sanitary, convenient method of storing open cereal is provided, with open boxes of cereal being kept fresh without necessitating continuous closing and opening of the inner, waxed bag. Further, the serving of the cereal is facilitated through the use of the pouring spout.

It is to be noted that the spout occupies the entire area of one end portion of the top wall of the cover portion. Thus, the spout has side walls which are low extensions of the side walls of the flange 26, reference here being had to the longitudinal walls of said flange 26 as distinguished from the transverse or end walls thereof. Said side walls of the spout 28 are coplanar with the corresponding side walls of flange 26. Further, the spout has a transverse wall at the extremity of the cover portion, which transverse wall is an upper extension of the corresponding end wall of the flange 26. In this way, the spout extends over the full area of the end portion of the top wall of the cover portion, so that when the cap is in open position, the contents can be poured laterally to either side, or alternatively, over the transverse outer end wall. This permits one to have maximum freedom of use

of the device, and to pour the container contents out in whatever fashion is most comfortable and handy for that particular person. Meantime, the cap, although also extending over the full width of the cover portion, is swung backwardly, fully out of the way regardless of whether the contents are being poured over the left-hand side, right-hand side, or outer end wall of the cover portion. The pouring action, of course, is the same in any of these three directions due to the fact that the spout is completely open, as distinguished from arrangements in which a spout may actually comprise a lid-like or cover member having perforations through which the container contents pass during the dispensing operation.

The device can of course be readily, cheaply formed of molded plastic or the like, and thus can be fully transparent, to permit the advertising material of the cereal carton to be displayed at all times. Of course, the cereal could be poured directly into the device, if the user so prefers.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

A cereal canister comprising an upwardly opening receptacle adapted for insertion of a disposable cereal carton therein; a cover portion for the receptacle comprising a flat top wall formed with a low, upwardly projecting, pouring spout, said cover portion further comprising a depending peripheral flange integral with said top wall, said flange being adapted to engage the upwardly opening receptacle and detachably grip the same to connect the cover portion removably to the receptacle, said flange of the cover portion being continuous over the full periphery of the cover portion and including longitudinal walls and transverse walls connected between the opposite extremities of the longitudinal walls, the spout including side walls formed as low, upper extensions of the respective longitudinal walls of the flange and

located in planes common to those of the corresponding longitudinal walls of the flange, said spout further including an outer end wall formed as a low, upper extension of one transverse wall of the flange, said spout being of rectangular formation and occupying the full transverse dimension of the cover portion at one end of the top wall of said cover portion; and a cap for the spout, said cap including a depending peripheral flange engageable about said spout and a support yoke formed from a length of thin rod material, said length being U-shaped so as to include a bight portion and legs projecting from the bight portion, the legs at the ends thereof remote from the bight portion being secured to said flange, the top wall including a transverse, upwardly projecting rib on which the bight portion is rotatably supported for pivotally mounting the cap on the top wall, said rib having an upwardly opening groove in which the bight portion is seated, the groove having a reduced top portion defining a reduced entranceway of the groove, said entranceway being slightly narrower than the diameter of the bight portion, the entranceway having springable side walls movable apart against the spring tension thereof to permit entrance of the bight portion of the support yoke, the opposed walls of the groove being continuous over the full length of the groove, said legs of the yoke bearing against the respective end surfaces of the groove walls, the legs engaging the end surfaces of one wall of the groove in the closed position of the cap, and engaging the end surfaces of the other wall of the groove in a full open position of the cap angularly spaced one hundred eighty degrees from said closed position of the cap, the cap when in its full open position lying substantially flat against the top wall wholly clear of the spout, to permit pouring of the container contents laterally in either direction out of the spout as well as forwardly over said end wall of the spout.
